UNITED STATES PATENT OFFICE.

RALPH K. MAKER, OF PROVIDENCE, RHODE ISLAND, ASSIGNOR TO JOSEPH GOLDSMITH JR., OF PROVIDENCE, RHODE ISLAND.

HAIR-CURLING DEVICE.

1,238,323.

Specification of Letters Patent. Patented Apr. 27, 1920.

Application filed December 5, 1919. Serial No. 342,668.

To all whom it may concern:

Be it known that I, RALPH K. MAKER, a citizen of the United States, and a resident of the city and county of Providence and 5 State of Rhode Island, have invented a certain new and useful Improvement in Hair-Curling Devices, of which the following is a specification.

This invention relates to a hair curling or 10 crimping device, and has for its object to provide a device of this character which receives and retains the hair and aids in producing a curled or wavy appearance of the hair.

15 This object is attained by means of my device, which comprises generally a strip of flat resilient material bent upon itself to form a pair of opposing arms, which receive, grip, press and crimp the hair between 20 them, a strand of hair usually being spirally wound on one of these arms and an improved arrangement being provided by means of which the ends of the arms are detachably locked together.

With these objects, and other objects which may hereinafter appear, in view, I have devised the particular arrangement of parts hereinafter set forth, and more particularly pointed out in the claims appended hereto.

Reference is to be had to the accompanying drawing, forming a part hereof, in which—

Figure 1 is a plan view of my improved 35 hair curling device in its closed position;

Fig. 2 is a side elevation of the device in open position;

Fig. 3 is a sectional view on the line 3—3 of Fig. 1, looking in the direction of the arrows;

Fig. 4 is a bottom view of the ends of the spring arms, showing the device for detachably locking the same together; and

Fig. 5 is a sectional view on the line 5—5 of Fig. 1, looking in the direction of the arrows.

Throughout the various views of the drawings, similar reference characters designate similar parts.

50 In the preferred embodiment of my invention, as illustrated in the accompanying drawing, the hair curling device is preferably constructed of a piece of flat, resilient material, transversely folded upon itself at 55 1 to form a loop 2, and a pair of oppositely

disposed, normally separated spring arms 3 and 4.

The arm 3 is brought down to a point 9 at its end, and the other arm 4 is provided with a locking device to receive and retain 60 the end of the arm 3. This locking device comprises a slidable sleeve 5, which is movable back and forth on the arm 4, and is restricted in its backward and forward movement by means of stops 6 and 7. The stops 65 6 and 7 are elongated protuberances formed by distorting or forcing outwardly the material of the spring arm 4 and are preferably in the form of transverse ribs as shown.

The sleeve 5 is provided with a narrowed 70 portion 8 which lies between the stops 6 and 7.

In using my improved hair curling device, a strand of hair is wound spirally about the arm 3, and the arms 3 and 4 are 75 pressed together while the slidable sleeve 5 is in position against the stop or abutment 7. When the two arms are brought together the sleeve 5 is moved to a position so that it abuts against the stop 6 and slides over the 80 tip or point of the arm 3 as will be seen in Figs. 1 and 3. To release the arm 3 the sleeve 5 is simply slid from over the end or tip of the arm 3 and the arms spring apart to the position shown in Fig. 2.

85 From the foregoing, it is obvious that my invention is not to be restricted to the exact embodiment shown, but is broad enough to cover all structures coming within the scope of the annexed claims.

90 Having described my invention, what I claim is:

1. A device of the class described, comprising a hair curler having two resilient arms, a slidable sleeve on one of said arms 95 adapted to be moved to engage the other arm and hold the ends of both of the arms together, spaced apart stops projecting from one face of the arm on which the sleeve is mounted, a narrowed portion of 100 said sleeve between the stops, said stops comprising protuberances formed by forcing outward the material of the arm on which the sleeve is mounted.

2. A device of the class described, comprising a hair curler having a pair of resilient arms, a slidable sleeve on one of said arms adapted to be moved to engage the other arm adjacent its end and hold both of 105 said arms together, said sleeve being pro- 110

- vided with a wide portion and a narrow portion, the wide portion being adapted to hold the arms together, a pair of stops on the arm on which the sleeve is mounted, 5 with the narrow portion of the sleeve situated intermediate of said stops.
3. A device of the class described, comprising a hair curler having a pair of arms, a pair of stops on one of said arms adjacent 10 the end of the same, a sleeve on said arm

slidable between the stops, said sleeve having a narrowed portion situated intermediate of the stops and a widened portion adapted to slide over the end of the other arm and hold both of the arms together. 15

Signed at the city and county of Providence, State of Rhode Island, this third day of December, 1919.

RALPH K. MAKER.
